DEODORANT CARRYING CONTAINER FOR USE
IN TOILET FLUSH TANKS

Roy P. Woodruff, 130 El Verano, Vallejo, Calif.

Filed Dec. 2, 1963, Ser. No. 77,638

Term of patent 14 years

(Cl. D16—2)

FIG. 2

FIG. 3

FIG. 1

FIG. 4

FIG. 5

FIG. 1 is a side view of a deodorant carrying container for use in toilet flush tanks showing my new design.

FIG. 2 is a top plan view of my design.

FIG. 3 is an end view taken from the left side shown in FIG. 1.

FIG. 4 is an end view taken from the right side shown in FIG. 1.

FIG. 5 is a bottom plan view of my design.

I claim:

The ornamental design for a deodorant carrying container for use in toilet flush tanks, as shown.
